(57) **CLAIM**

The ornamental design for scoreboard in the form of a hot air balloon, as shown and described.

DESCRIPTION

FIG. 1 is a front view of a scoreboard in the form of a hot air balloon showing our new design;

FIG. 2 is a top view thereof;

FIG. 3 is a bottom view thereof;

FIG. 4 is a side view thereof; and,

FIG. 5 is another side view thereof.

The broken lines showing the environment are for illustrative purpose only and form no part of the claimed design.
